UNITED STATES PATENT OFFICE.

PAUL P. SCHROEDER, OF GREENWICH, CONNECTICUT.

RADIO LOUD-SPEAKER.

Application filed May 31, 1927. Serial No. 195,318.

My invention relates to improvements in radio loud speakers, and has a more particular reference to that type of loud speaker wherein a paper or parchment material is employed as the ultimate tone producing agent.

Heretofore considerable criticism has been directed against the operation of these parchment diaphragm speakers. The most important of the imperfect qualities of this type of speaker is due to the construction of same, whereby the extreme high and low oscillations are drowned by attempted impressions on a single diaphragm of a given resonance.

In these conventional speakers, a single diaphragm is employed which must accommodate both the extreme high and low oscillations. In other words, a single diaphragm is provided which must emit vibrations of varying high and low pitches.

An object of my invention is to overcome this imperfect condition and the elimination of the almost frequent intolerable sound emissions from the distortion of the diaphragm caused by one amplitude of oscillations overcoming and drowning an accompanying group.

To produce this desired result, I have provided a loud speaker wherein I employ two or more diaphragms of varying sound producing qualities. These diaphragms are actuated by the vibrations of a single electro-magnetically operated diaphragm unit, so that the amplitude of oscillations flowing the articulated circuit will become partial to the respective diaphragms of corresponding resonance.

In the drawings:—

Figure 1 is a perspective view of the preferred construction of my invention in its entirety.

Fig. 2 is a vertical sectional view of the same, showing the means employed for vibrating the several diaphragms.

In the drawing wherein like numerals designate like parts of my invention, a box-like structure 1 is provided with suitable supporting members 2 for supporting an electro-magnetic diaphragm unit 3 of conventional construction. This unit is provided with the usual electro-magnetic coils and the usual diaphragm vibrated through the attraction of the magnetic coils.

The top of this box-like structure is closed

by a suitable panel 4, or else the top may be actually left open if desired. The front wall of this structure is formed of a two-ply panel 5 having openings 6 formed therein and further formed with a pair of enlarged circular openings 7 in open registry to each other. The low tone diaphragm 8 of larger diameter than the circular openings in the pair of front panels, is constructed of preferably a disk of substantially stiff parchment and with the outer edge portion thereof being held between the circumferential edge portions of the annular opening.

The remaining walls 9 of this box-like structure including the bottom wall 13, are preferably of thin paper material and are considerably larger in area than the diaphragm 8 of the front wall. These thin paper walls are in themselves diaphragms, and are provided along with the low tone diaphragm of the front wall with buttons 10 located centrally on the inner sides thereof.

Connected to these buttons, are connecting wires 11 which radiate from a central wire 14 having its lower extremity connected to the button on the inner side of the bottom wall 13. These wires are of a semi-rigid metal and are preferably of steel. The wires 11 in arrangement are inclined from the button on the side walls to their point of connection to the central wire 1. Suitable feet or leg members 14 are provided for supporting the structure.

In operation, while the coils of the unit 3 are electrically energized, the consequential vibration of the diaphragm thereof, is transmitted through the central wire 14, and distributed over the radial wires 11, to their respective diaphragms.

Now it will be seen that some vibrations will be too weak or extremely too frequent for registration on the high resonance diaphragm, but as the wires become sensitive to the more intent and prolonged vibrations, the low resonance diaphragm will then be set in motion. Thus, the low tone diaphragm will not be attracted by the high pitch tones, but will only be susceptible of low tone vibrations.

Having thus described my invention, what I claim as new is:—

In a sound reproducing device including a vibratory unit, a plurality of diaphragms of varying resonance arranged in angular rela-

tion to each other, a strand of semi-rigid material connected at one end to the vibratory unit, a yieldable structure to which the opposite end of said flange is attached, said strands being disposed in substantially axial relation to the diaphragm, and a branch strand connecting each of the diaphragms to the axial

strand, said branch strands being of semi-rigid material, each of which is connected to the axial strand in oblique respect to its dia- 10 phragm.

In testimony whereof I affix my signature.

PAUL P. SCHROEDER.
